UNITED STATES PATENT OFFICE.

HENRY B. QUEAL, OF KEWANEE, ILLINOIS.

ROTARY DRINK-MIXER.

1,119,370.

Specification of Letters Patent.

Patented Dec. 1, 1914.

Application filed November 7, 1913. Serial No. 799,798.

To all whom it may concern:

Be it known that I, HENRY B. QUEAL, a citizen of the United States, residing at Kewanee, in the county of Henry and State of Illinois, have invented certain new and useful Improvements in Rotary Drink-Mixers, of which the following is a full, clear, and exact description.

This invention relates to improvements in rotary drink mixers of the type such as are used in drug-stores, soda fountains, etc.

Among the salient objects of the invention are to provide a rotary mixer in which the rotating spindle is simply and positively driven by a jet of compressed air or gas; to provide an improved mixer in which the necessity of supplying electric power is dispensed with and the disagreeable whine or buzz generally associated with electrically driven devices is obviated; to provide an improved construction whereby the compressed air or gas is conducted to the impeller wheel of the mixer inconspicuously and conveniently, and in which the spent gas, after doing its work, is conducted away from the impeller wheel quietly and inconspicuously; to provide means for raising the agitator member out of the tumbler or receptacle containing the liquid without being obliged to lift the entire device; to provide a construction which will be suitable for all sizes of receptacles and all classes of liquids; to provide a construction which shall be simple mechanically, economical of construction, and which is not liable readily to get out of order; and in general to provide an improved apparatus of the character referred to.

Referring to the drawings,—Figure 1 shows my improved drink mixer in side elevation, parts of the apparatus being shown broken away more clearly to show the mechanical construction of the device; Fig. 2 is a sectional plan of the casing along the line 2—2 of Fig. 1; Fig. 3 is a sectional view of the valve adapted to control the air supply; Fig. 4 is a perspective view of a modified form of agitator button; and Fig. 5 is a cross-sectional plan of the agitator button shown in Fig. 4.

Similar figures refer to similar parts throughout the several views.

Referring to the drawings,—in Fig. 1, 1 is a hollow standard, preferably circular in cross section, provided with a tripod base 2. The base 2 is furnished with three soft

rubber buttons 3, which prevent marring of the table or counter when the mixer as a whole is moved around. Upon the top of the standard 1 is rigidly attached a hollow casing 4, which is preferably a circular casting with an integral boss 5, into which fits the standard 1. The top of the casing 4 is provided with screw threads 5', to which is threaded a circular cover 6. The cover 6 and the casing 4 are of such a curvature that when the cover 6 is screwed onto the casing 4, a spherical construction results, with no projections to catch dust or catch in the clothing of the operator. The casing as a whole is provided with a spindle 7 loosely mounted therein in a vertical position. Loosely mounted upon the spindle 7 and in the center of the casing is an impeller wheel 8, which has a hollow sleeve 9 projecting through the top of the casing and forming a bearing for the spindle 7. The sleeve 9 has a notch 10 of V-shape extending across the diameter of the top of the sleeve, and in this notch is a pin 11 tightly fixed in the spindle 7 and projecting slightly at each end. On the upper end of the spindle 7 is screw-threaded a finishing button 13, the latter being counterbored at its lower end to admit the upper end of the sleeve 9. It will thus be seen that if the spindle 7 be lifted vertically a short distance, the pin 11 will rise out of the V-shaped notch in the end of the sleeve 9, leaving the impeller wheel 8 free to revolve without rotating the spindle. Again, when the spindle is in its lowest position, as shown in Fig. 1, if the impeller wheel is rotated, the spindle will also revolve, due to the pin 11 co-operating with the notch 10 in the sleeve of the impeller wheel.

Referring more particularly to the details of construction of the impeller wheel, upon the sleeve 9 is fixed a strengthening collar 14 which carries the impeller wheel proper 8. The latter is preferably stamped from a single piece of sheet-metal to form a series of radially extending arms 14', which carry a series of cone-shaped impeller blades or cups 15. I have found in practice that the construction of impeller wheel just shown is particularly adapted for the present construction. Within the standard 1 is a supply pipe 16, the lower end of which is connected as shown at 17 to a rubber hose 18 leading to any suitable source of compressed air or gas. The upper end of the supply pipe 16, as shown in Fig. 2, is soldered or

otherwise fixed to the inside of the hollow standard 1, so that the supply pipe is located as near to the circumference of the circular part of the casing 4 and the outer 5 circumference of the impeller wheel as possible. At a point coincident with the center of the impeller wheel is a nozzle orifice 19, the lips 20 of which are so shaped as to deliver a jet of air or gas in such a direction as to coöperate with the buckets of the 10 impeller wheel to the best advantage. The top of the supply pipe 16 projects up through the closed top 20' of the casing boss, and the end of the pipe is bored out 15 for a distance extending down below the nozzle 19 far enough to provide a bearing for the plug valve 21, which is a tube closed at the top and open at the bottom, with a longitudinal slot or valve port 22 which 20 registers with the port 19 when the plug is turned in a certain position, thus admitting air or gas to the nozzle. To the plug 21 is fixed a stem 23, which carries a handle 24, and leakage of gas or air is prevented 25 by the gland 25, provided with suitable packing and screwed onto the top of the tube 16. Adjustably mounted on the outside of the standard 1, is a sliding bracket 26, which is furnished with a table 27 for supporting 30 the glass or receptacle 33 containing the liquid, and a set screw 28 for adjusting and fixing the location of the bracket upon the standard. Upon the end of the spindle 7 is screwed an agitator button 29, which is 35 approximately conical in shape and provided with notches 30, which serve the purpose of breaking up the different strata of the liquid, and thus effecting a more perfect agitation of the fluid. To permit the escape 40 of the exhaust air or gases between the casing 4 and the hollow standard 1 is a port 35, which furnishes an escape opening, the exhaust air or gases traveling down the hollow standard and out of its lower open 45 end. The exhaust is thus inconspicuous and practically noiseless.

In Figs. 4 and 5, I show a form of button which in some instances may be preferable to the button shown in Fig. 1. It will be 50 seen that the button 31 is substantially cylindrical in cross section and provided with notches 32, the latter being much deeper at the bottom than at the top of the button, and also being cut slantwise across the face 55 of the button. The effect of this is to provide a churning effect through the liquid, and cause a steady current from the top to the bottom of the receptacle during the mixing operation.

60 The operation of the mixer is obvious from the above description of its construction. The table 26 is adjusted upon the standard in such a position that when the spindle 7 is in its lowermost position, the 65 button 29 will be at the proper distance

from the bottom of the glass to provide the maximum efficiency and greatest mixing effect. The glass 33 being full of liquid, it is necessary to raise the spindle 7 by pulling up upon the finishing button 13 a sufficient distance to slide the glass under the agitator button 29, the upper position of the latter and of the shaft being shown in dotted lines on Fig. 1. When the glass is in place, the spindle 7 is lowered and mixing effected by opening the valve 24. The removal of the glass 33 is similarly effected by again raising the spindle 7 high enough to avoid interference with the agitator button 29.

I do not wish to limit myself to the details of construction shown except as specified in the appended claims.

I claim:

1. In a mixer, the combination with a supporting standard, of a substantially air-tight casing having inlet and outlet ports through which compressed air or gas is driven, of a rotary impeller wheel mounted in said casing, an agitator member having a drive shaft extending into said casing, and operative connections between said shaft and impeller wheel.

2. In a mixer, the combination with a supporting frame member, of a substantially air-tight casing mounted thereon and provided with inlet and exhaust ports, an impeller wheel in said casing and driven by a current of air or gas forced through said casing, an agitator member, a drive shaft therefor, and operative connections between said wheel and shaft.

3. In a mixer, the combination with a hollow supporting standard open at its lower end, of a closing casing member mounted on said standard and having an inlet and exhaust port, the latter opening into said hollow standard, a gas or air supply pipe in said standard and communicating with said inlet port, an impeller wheel in said casing, a drive shaft operatively connected to said shaft, and an agitator member driven by said shaft.

4. In a drink mixer, the combination of a supporting standard, a closing casing mounted on said standard and provided with an inlet and an exhaust port, an impeller wheel mounted within said casing and adapted to be driven by a current of air forced through said casing, a sleeve projecting from the top of said casing, an agitator member, a drive-shaft therefor extending downwardly through said sleeve and from the casing, and gravity-retained engaging means operatively connecting the upper ends of said sleeve and shaft.

5. In a drink mixer, the combination of a closing casing, an agitator member, a vertical drive shaft for said agitator member passing through the center of said casing, a

sleeve supported by the bottom of said casing surrounding said shaft and projecting from the top of said casing, an impeller wheel mounted on said sleeve, and means for 5 operatively connecting the top of said sleeve and said shaft.

6. In a mixer, the combination of a supporting casing, rotary driving means contained within the casing, a drive shaft projecting from the top and bottom of said casing and longitudinally slidably with reference to said rotary driving means, and means for operatively connecting said shaft with said rotary driving means when the 10 shaft is in its lowermost position, said shaft being operatively disconnected from said rotary driving means when raised from said lowermost position.

7. In a mixer, the combination of a substantially air-tight casing provided with inlet and exhaust ports, an impeller wheel in 20 said casing driven by a current of air or gas forced through said casing, a drive shaft slidably mounted within said casing and 25 projecting downwardly therefrom, an agita-

tor member on the lower end of said drive shaft, and means for effecting operative connection between the drive shaft and the impeller wheel when the drive shaft is in its lowest position.

8. In a drink mixer, the combination of a circular casing, a vertical sleeve rotatably mounted within, supported by the bottom of and projecting from the top of said casing, an impeller wheel mounted on said sleeve 30 and adapted to be driven by a supply of air admitted to said casing, an agitator member, and a drive-shaft therefor slidably mounted within said sleeve and projecting from the top and bottom of said casing, said drive-shaft having at its upper projecting end a projection adapted to engage a notch in the upper end of said sleeve.

In witness whereof, I hereunto subscribe my name this 3d day of November, A. D., 40 1913.

HENRY B. QUEAL.
